(57) **CLAIM**

The ornamental design for a display panel portion with an animated graphical user interface, as shown and described.

DESCRIPTION

FIG. 1 is a front view of a first image in a sequence for a display panel portion with an animated graphical user interface, showing our new design;

FIG. 2 is a front view of a second image in the sequence thereof;

FIG. 3 is a front view of a third image in the sequence thereof;

FIG. 4 is a front view of a fourth image in the sequence thereof;

FIG. 5 is a front view of a fifth image in the sequence thereof;

FIG. 6 is a front view of a sixth image in the sequence thereof; and,

FIG. 7 is a front view of a seventh image in the sequence thereof.

The appearance of the transitional image sequentially transitions between the images shown in FIGS. 1-7. The process or period in which one image transitions to another image forms no part of the claimed design.

The broken lines showing a portion of a display panel and portions of the animated graphical user interface in FIGS. 1-7 form no part of the claimed design.
